Primary Examiner — Rachel A. Voorhies*Assistant Examiner* — Benjamin D. Wannemacher(74) *Attorney, Agent, or Firm* — Scully, Scott, Murphy & Presser, P.C.(57) **CLAIM**

The ornamental design for a torque wrench, as shown and described.

DESCRIPTION

FIG. 1 is a front-side view of a torque wrench showing my new design;

FIG. 2 is a front-left perspective view thereof;

FIG. 3 is a front-right perspective view thereof;

FIG. 4 is a back-left perspective view thereof;

FIG. 5 is a back-side view thereof;

FIG. 6 is a right-side view thereof; and,

FIG. 7 is a left-side view thereof.

The broken lines shown in the Drawings illustrate portions of the torque wrench that form no part of the claimed design.
